CLAIM

The ornamental design for a parturition drape, as shown and described.

DESCRIPTION

This application is related to U.S. application Ser. No. 17/008,948, which is filed concurrently herewith and entitled “Dual Amniotic and Placenta Fluid Measurement Parturition Drape,” and which is incorporated by reference for all purposes.

FIG. 1 is a front elevation view of a parturition drape, showing my new design in an unfolded configuration;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a first perspective view thereof; and

FIG. 8 is a second perspective view thereof;

FIG. 9 is a first perspective view of the parturition drape in the unfolded configuration with a first pouch of the parturition drape partially opened; and

FIG. 10 is a second perspective view thereof.

FIG. 11 is a first perspective view of the parturition drape in the unfolded configuration with a second pouch of the parturition drape partially opened; and,

FIG. 12 is a second perspective view thereof.

All broken lines are included for the purpose of illustrating portions of the parturition drape that form no part of the claimed design.
